AIR CIRCULATING APPARATUS

Henry S. Woodruff, Larchmont, and Paul T. Engelskirchen, Jr., Mount Vernon, N. Y., assignors to American Radiator Company, New York, N. Y., a corporation of New Jersey

Application July 16, 1935, Serial No. 31,584

17 Claims.

(Cl. 98—94)

This invention relates to air translating apparatus, and more particularly to devices for circulating air in rooms of buildings, and the like.

We have shown in the accompanying drawings, 5 our invention as embodied in a window ventilator adapted to be arranged in an opening defined by a partially raised window sash and a window sill and operable to force outside fresh air into a room. It is understood, however, that in so 10 far as certain of the broader aspects of our invention are concerned, it is not to be considered as limited to this particular type of construction or to this particular use.

The objects of our invention are to provide a 15 device for circulating air which is simple in construction and operation and can be easily and quickly installed; one which is comparatively quiet in operation; one which is capable of circulating a relatively large volume of air per unit of time for a given size of device; one which is provided with a relatively large air outlet and delivers air through all portions of the outlet at substantially the same desired velocity and pressure; and lastly, one which can be easily and 20 quickly assembled and disassembled and is relatively inexpensive to manufacture.

The invention consists in the novel construction and combination of parts, to be more fully described hereinafter, and the novelty of which will 25 be particularly pointed out and distinctly claimed.

In the accompanying drawings, to be taken as 30 a part of this specification, we have fully and clearly illustrated a preferred embodiment of our invention, in which drawings

Figure 1 is a plan view showing a window 35 ventilator constructed in accordance with our invention as installed in a window opening and operating to deliver clean fresh air into a room;

Figure 2 is a front elevation of the window 40 ventilator illustrated in Figure 1;

Figure 3 is a transverse vertical section of the 45 device, the section being taken on the line 3—3 of Figure 2;

Figure 4 is a perspective view showing certain 50 elements of our device formed as a unit which may be readily removed and assembled in an enclosing casing;

Figure 5 is a longitudinal vertical section 55 through the device, the section being taken on the line 5—5 of Figure 3;

Figure 6 is a detail fragmentary sectional view 55 illustrating the manner in which adjustable louvers are mounted in an air outlet of the enclosing casing structure and the manner in which the louvers are operated;

Figure 7 is a fragmentary detail view showing in horizontal section the adjustable louvers and the operating means therefore the section being taken on the line 7—7 of the Figure 2;

Figure 8 is a fragmentary view showing in elevation a portion of the end wall of the casing structure and the lever for operating a damper disposed within the enclosing casing; and

Figure 9 is an exploded view showing in transverse section the detail construction of the enclosing casing structure and the manner in which the cover of the casing may be quickly removed and replaced to facilitate assembly and repair, the section being taken on the line 9—9 of Figure 2.

Referring now in detail to the accompanying drawings, the reference numeral 10 indicates a window ventilator in its entirety which, as shown, may be removably supported in position to receive outside air through an opening 11 defined by a lower sash rail 12 of a window, a window sill 13 and the sides 14 of the window casing (see Figs. 1, 2, and 3). The ventilator rests at its rear on the window sill 13 and is provided on its bottom with a pair of parallel transversely extending supporting strips 15 which are in turn supported from their outer ends by diagonal brackets 16, the latter being secured at their lower ends within socket members 17 fixed to the side wall 18 of the room beneath the window sill.

The spaces between the ends of the ventilator 10 and the sides of the window casing may be filled by suitable blocks 19. A strip 20 of felt, rubber or similar material may be disposed between the bottom of the ventilator and the window sill, and a second strip 21 of similar material may be secured to the upper rear longitudinal edge of the ventilator for engaging the lower sash rail 12. The purpose of the felt strips 20 and 21 and the filler blocks 19 is to prevent the entrance into the room of outside street noises and the like, and, as will presently appear, to permit the entrance of only clean fresh air into the room.

The ventilator 10 includes an enclosing casing structure 22 and the latter comprises a rear or back wall 23, a bottom wall 24, a front wall 25, a top wall 26, and end walls 27 and 28.

The rear wall 23 is provided with an air inlet 29 extending for the full length and height of the casing and communicating through the window opening 11 with the outside atmosphere. A filter 30 is removably secured within vertical guides 31 fixed to and forming a part of the rear wall 23. The filter is arranged immediately behind and

across the full length of the inlet 29, thereby assuring that the outside air entering the ventilator will be thoroughly cleaned. A plurality of fixed louvers 32 extend lengthwise of the air inlet 29 and serve to prevent rain, snow and the like from entering the ventilator. The louvers 32 are in the form of plates disposed diagonally downwardly as shown, to provide upwardly inclined air passages 33 for the entering air. Flanges 34 10 are provided on the ends of the louvers 32 for securing them to the ends of the rear wall 23.

The bottom wall 24 is provided with a pair of parallel and spaced positioning members 35 and 36 extending for the full length of the casing, the 15 member 35 being angle-shaped in cross section, with the upstanding flanges 37 thereof arranged toward the rear of the casing, and the member 36 being channel-shaped in cross section and having an upstanding flange 38 parallel to and spaced 20 from the flange 37 (see Fig. 9). The members 35 and 36 may be securely fixed to the bottom wall by any suitable means, such for example, as spot welding. The bottom wall 24 is provided on the front and ends thereof with an upstanding flange 39. The lower edges of the front wall 25 and the end walls 27 and 28 fit on the inside of the flange 39, as shown in Figs. 3 and 5. The positioning members 35 and 36 and the flange 39 25 also function to stiffen the bottom wall 24.

30 The front wall 25 is provided with an air outlet 40 which extends for substantially the entire length of the casing and is divided in the middle into a pair of openings 41 and 42 by a narrow vertical member 43 formed as part of the front wall 25 and lying flush with the remaining portions of the front wall. A plurality of adjustable louvers 44 are arranged within each of the openings 41 and 42 and are pivotally mounted to turn on horizontal axes. The louvers serve to direct the outgoing air either upwardly and forwardly of the casing, downwardly and forwardly of the casing, or to close the openings 41 and 42. Figs. 2, 3 and 9 show the position of the louvers when in closed position. Fig. 6 shows in full lines the position of the louvers for directing the air upwardly and forwardly and in dotted lines the position of the louvers for directing the air downwardly and forwardly.

An operating lever 45 serves to move all of the louvers 44 in unison to either of the three positions just explained. The openings 41 and 42 are defined respectively by inturned flanges 46 and 47 of the front wall. The louvers 44 are pivotally mounted at their ends adjacent the end walls 27 and 28 by pins 48 (see Fig. 2), which pins extend through the ends of their respective louvers at the centers thereof and through openings in the flanges 46 and 47. The louvers are pivotally mounted at their ends adjacent the vertical member 43 by pins 49 extending through the ends of the louvers at their respective centers and through aligned openings in the flanges 46 and 47. The pins 48 are relatively short and are secured in place by riveting after the louvers 44 are in place. The pins 49 are relatively long and each of these pins extends across the vertical member 43 at the rear thereof and serves as a pivot for corresponding or adjacent louvers in the openings 41 and 42.

Each of the louvers 44 at the end thereof adjacent the vertical center member 43 is provided with a flange 50 extending rearwardly and inwardly of the casing, and the flanges 50 of all of the louvers are connected together by vertical links 51 and cross pins 52 for operation in

unison. The two center louvers in the opening 41 are connected across to the corresponding center louvers in the opening 42 by the pins 52 extending through aligned openings in the flanges 50, and each link 51 connects together all of the louvers 44 of each opening. Each link 51 is connected at its opposite ends to the flanges 50 of the top and bottom louvers of one of the openings and is connected intermediate its ends to the cross pins 52 which, as stated, connect corresponding intermediate louvers. The operating lever 45 is pivotally mounted on one of the pins 49 and is operatively connected at the end thereof inside of the casing 22, to the lowermost cross pin 52 by a slot 53 formed in the end of the lever and receiving the pin 52. Thus, the louvers 44 may be moved in unison to either of the three positions by grasping the knurled outer end 54 of the lever and moving it up or down, as desired.

The top wall 26 is provided with an air outlet 60 which extends for substantially the full length of the casing and is divided in the center by a transversely extending narrow strip 61 to form two openings 62 and 63. A single louver 64 is 25 mounted in each of the openings 62 and 63, and each louver is mounted in its respective opening to swing about a pivot located adjacent its forward longitudinal edge. The pivotal mounting for each louver 64 is effected by pins 65 extending through aligned openings in the ends of the louver and in flanges 66 depending from the top wall at the ends of each of the openings 62 and 63. The louvers 64 may be moved up to the dotted line position shown in Fig. 3 or they 30 may be closed, as desired, by grasping an upstanding knob 67 fixed to the upper side of each of the louvers. When the louvers 64 are opened to the dotted line position, the air is directed upwardly and rearwardly and against 35 the window and thereby diffused upwardly into the room. The louvers 64 are prevented from being moved past their full open and full closed positions by pins 68 extending from the flanges 66 and adapted to engage either of two space 40 abutments 69 and 70 formed on flanges 71 depending from each end of each of the louvers.

The rear longitudinal edge of the top wall 26 defines with the top of the rear wall 23, an opening 72 extending lengthwise of the casing and through which the filter 30 may be inserted and removed. A removable cover plate 73 covers this opening and the upper surface thereof lies flush with the upper surface of the top wall 26. An angle 74 extends longitudinally of the casing adjacent the upper ends of the vertical guides 31 for the filter, and is fixed to the guides. An upper horizontal flange 75 of the angle 74 serves as a ledge upon which the rear edge of the top wall may rest and be secured.

The end walls 27 and 28 of the casing may be formed from the same strip of metal as the front wall, and the end walls extend rearwardly and overlap the portion of the rear wall forming the guides for the filter, as indicated at 76. The top wall 26 may be formed as a separate piece and provided with a downwardly extending flange 77 along its front and end edges, which flange overlaps and is fixedly secured to the upper edges of the top and end walls.

In order to facilitate manufacture, assembly and repair, the casing 22 is divided structurally into two pieces; the rear and bottom walls 23 and 24 respectively, being secured together to form one piece, and the front wall 25, end walls 75

27 and 28 and top wall 26 being secured together to form a removable cover piece. The cover piece is removably secured in place on the bottom and rear walls by removable screws 78 extending through the upturned flange 39 of the bottom wall 33 and through the front wall, and through the rear edge of the top wall and the flange 75 of the angle 74 fixed to the rear wall.

10 The casing is divided longitudinally by an upright partition 80 into a rear inlet chamber 81 communicating through the passages or interstices of the filter 30 and the inlet 29 with the atmosphere, and a front outlet chamber 82 communicating through the front wall outlet 40 and top wall outlet 60 with the room. The partition 80 comprises a lower vertical portion 83 spaced from and parallel to the front wall 25, an intermediate diagonal portion 84 sloping upwardly 15 and rearwardly from the top of the lower portion 83, and an upper deflecting portion 85 curved upwardly and forwardly from the top of the intermediate portion 84 to the top wall 26 of the casing (see Figs. 3, 4, and 5).

25 The intermediate diagonal portion 84 is provided with a pair of openings 86 and 87 which are disposed symmetrically at opposite sides of a transverse median plane through the casing, and the openings 86 and 87 provide communication between the rear inlet chamber 81 and the front outlet chamber 82. A pair of centrifugal blower housings 88 and 89 are arranged in the inlet chamber 81 with their outlets communicating with the openings 86 and 87 respectively. 30 Each of the blower housings is provided at opposite sides thereof with inlets 90 communicating with the inlet chamber 81 and arranged in planes extending transversely of the casing and parallel to one another.

40 The upper portions of the blower housings are fixed to the intermediate portion of the partition by any suitable means, such, for example, as riveting or spot welding. The lower portions of each of the housings are secured by connecting 45 strips or plates 91 and 92 to a channel-shaped supporting member 93 extending longitudinally of the bottom wall 24 of the casing. The plates 91 are suitably secured by spot welding at their lower ends to an upstanding flange 94 of the supporting member 93 and at their upper ends 50 are riveted to the rear side of the blower housings 88 and 89. The plates 92 are spot welded at their lower ends to a second upstanding flange 95 of the member 93 and at their upper ends are riveted to the front side of the blower housings.

55 The channel-shaped supporting member 93 is positioned on the bottom wall 24 by the flanges 37 and 38 of the members 35 and 36 respectively, and the member 93 is removably secured at each 60 end thereof to the bottom wall 24 by bolts 96 and wing nuts 97 (see Fig. 5). The bolts 96 extend upwardly through aligned openings provided respectively in the bottom wall 24, in the base of the member 93 and in transverse pieces 98 disposed across and securely fixed to the member 93 at each end thereof. The wing nuts 97 are threaded to the upper ends of the bolts, as shown.

An electric motor 100 is disposed between the blower housings 88 and 89 and is supported by a member 101 having depending flanges 102 at the ends thereof which are fixedly secured to the supporting member 93. The motor 100 is secured to the member 101 by a U-shaped bracket 103 having arms 104 secured at their upper ends to the ends of the motor housing and hav-

ing a lower portion 105 suitably secured to the base member 101 by screws 106. The motor 100 has a shaft 107 which extends out both ends of the motor and through the inlet openings 90 of the blower housings 88 and 89, respectively. A 5 pair of centrifugal blower elements 108 are disposed within the housings 88 and 89, respectively, and are fixed to the outer ends of the motor shaft 107.

In operation, the motor driven centrifugal 10 blower elements 108 provide for the flow of air from the inlet chamber 81 through the openings 86 and 87 in the partition 80 into the outlet chamber 82, and through either or both of the outlets 40 and 60 into the room. 15

The speed of the motor may be regulated by a rheostat 110 disposed within a housing 111 arranged at the forward side of the vertical portion 83 of the partition 80. A control shaft 112 for the rheostat extends through the housing 111 and 20 the front wall 25 of the casing and a knurled knob 113 on the outer forward end of the shaft serves to regulate the rheostat.

The lower end of the vertical portion 83 of the partition 80 is fixedly secured to the flange 95 25 of the supporting channel 93 and the housing 111 is fixedly secured to the vertical portion 83. Any suitable means may be used for securing together the housing 111, lower end of the vertical portion 83 and flange 95; for example, they may 30 be secured together by riveting or spot welding.

From the above description, it will be seen that the partition 80, the blower housings 88 and 89, the rheostat 110 and housing 111 therefor, and the motor 100 are all securely fastened to the 35 supporting member 93 and that the latter is removably secured to the bottom wall of the casing by the bolts 96 and wing nuts 97. These elements form an assembled unit and as such may readily be installed in and removed from the 40 casing. The decided utility of this construction in facilitating assembly and repair of the ventilator will be readily appreciated.

A damper 115 extends longitudinally of the casing in the outlet chamber 82 and is fixedly 45 secured along its upper longitudinal edge to a shaft 116 journaled in the end walls 27 and 28, respectively, of the casing. One end of the shaft 116 extends exteriorly of the casing and has secured thereto an operating lever 117 (see Figs. 3, 50 5, 8, and 9). By moving the lever 117, the damper 115 may be moved to the dotted line position shown in Fig. 3 to close off the space between the forward edge of the curved deflecting portion 85 of the partition and the lower edge of 55 the diagonal portion 84 and thereby prevent the passage of air through the casing, or the damper 115 may occupy the position shown in full lines and thereby form a defining wall element of an air passage through the casing. When the 60 damper is in open position, the lower edge thereof is spaced from the front wall 25 so that air may flow around the lower edge of the damper and upwardly and out of the openings 62 and 63 in the top wall, when the louvers 64 are open.

65 The inlet and outlet chambers 81 and 82 and blower housings 88 and 89 provide a passage through the casing for fresh air. A portion 118 of this passage is defined by the upper surface of the intermediate diagonal portion 84 of the partition 80 and by the bottom surface of the deflecting portion 85 and by the rear surface of the damper 115. This portion 118 of the passage extends downwardly and forwardly toward the outlet openings 41 and 42 in the front wall. The 70 75

interior surface of this portion of the passage, as well as all interior surfaces of the inlet chamber, are provided with a lining of sound deadening or absorbing material 119 of any suitable kind; for example, acoustic felt.

As stated, one purpose of the damper 115 is to close the air passage through the casing and thereby prevent the flow of air therethrough when the device is not in use. The closing of the passage is made more effective by the presence of the relatively soft sound deadening material 119 on the engaging surfaces of the damper and intermediate portion 84 of the partition. If desired, portions of the inlet chamber 81 may also be provided with a lining of sound deadening material 120 to prevent the passage of motor and blower noises through the casing walls.

On account of the diagonal arrangement of the intermediate portion 84 of the partition and the forwardly curved surface of the upper portion 85, and the arrangement of the openings 86 and 87 and the blower housings 88 and 89, a relatively large amount of air per unit of time can be circulated through a casing of a given cross sectional dimension and length. The forwardly curved portion 85 and the damper 115, in conjunction with the upper surface of the diagonal portion 84 and the forward surface of the vertical portion 83, provide a tortuous air passage which aids in effectively absorbing sound. As this tortuous air passage is as wide as the casing structure is long and as the passage is curved in vertical planes, the maximum air capacity for a given size of casing is made possible and at the same time air is ejected from the outlets 40 and 60 at substantially the same velocity and pressure throughout their length.

The louvers 44 in the inlet 40 provide for directing the air to different portions of the room forwardly of the casing. In case the movement of air into the room through the louvers 44 in either of the directions provided for should be uncomfortable to the occupants of the room due to the creation of drafts, the louvers 44 may be closed and the louvers 64 in the top wall outlet 60 opened. The air will then flow around the end of the damper 115 and between the latter and the front wall of the casing and upwardly through the outlet 60. As the louvers 64 in their open position are inclined rearwardly, the air leaving the casing through the outlet 60 will be directed upwardly and rearwardly and against the window pane and side wall of the room, from whence it will be distributed throughout the room without creating drafts.

From the foregoing description, it will be seen that our improved form of air circulating device is divided structurally into three separate units for the purpose of facilitating manufacture, assembly, and repair. One of the units is composed of the back wall 23 and bottom wall 24, which are rigidly secured together and mounted in position in a window opening 11 or the like, and independently of the remaining portions of the ventilator. The second of these units consists of the supporting member 93 with the partition 80, blower housings 88 and 89, rheostat housing 111 and rheostat 110, and motor 100 with its shaft 107 carrying the blower elements 108, all firmly secured to the supporting member 93. The second unit may be readily removed from the casing as previously explained. The third of these units is the cover consisting of the front wall 25, top wall 26 and end walls 27 and 28 with the shaft 116 and damper 115 assembled

therein. The cover is detachably secured to the unit first referred to in a manner already described.

It is to be understood that, while we have illustrated our invention as being embodied in a ventilator adapted to be installed in a window, our invention in all of its aspects is not so limited. In so far as certain of the broader aspects of our invention are concerned the novel features may be embodied in a number of different devices; for example, the features of the invention may be embodied in devices for recirculating air in a room, or for introducing outside air into the room through openings other than those provided by a partially opened window.

What we claim and desire to secure by Letters Patent of the United States is:

1. An air circulating device comprising a casing structure including an upright front wall having an air outlet extending for substantially the entire width thereof; means in said casing defining an air passage communicating with the outlet and extending through the casing in a direction toward the front wall and being of substantially the same width as the front wall outlet opening; said passage-defining means including spaced upper and lower wall elements extending for the full width of the passage, and the upper wall element being inclined downwardly and forwardly toward the air outlet in the front wall for directing the air toward said outlet; the upper wall element being pivotally mounted at its upper end to move about a horizontal axis extending substantially parallel to the plane of the front wall; means for moving the upper wall element about said axis and toward the lower wall element so as to close the air passage and prevent the flow of air therethrough; and means providing for the flow of air through said passage and the outlet.

2. A window ventilator comprising an elongated casing adapted to be arranged crosswise of an opening defined by the lower portion of a partially raised window sash and a window sill and including a rear portion having an air inlet extending lengthwise of the casing to communicate with the outside atmosphere and a front portion having an air outlet extending lengthwise of the casing to communicate with a room; an upright partition dividing the casing longitudinally into a rear inlet chamber communicating with the inlet and a front outlet chamber communicating with the outlet; said chambers extending for substantially the entire length of the casing; the partition including an upright lower portion spaced from the front of the casing and extending in the same general direction as said front portion, a diagonal intermediate portion extending backwardly and rearwardly from the top of the upright lower portion, and a top portion extending upwardly and forwardly from the top of the diagonal portion and defining with the diagonal portion an air passage extending for substantially the same length of the casing as the air outlet and communicating with the latter; said diagonal portion having an opening therein providing communication between the inlet and outlet chambers; and blower means arranged to discharge air upwardly through said opening in the diagonal portion and toward said top portion.

3. An air circulating device for a room comprising a casing including a front wall having an air outlet extending for substantially the full length thereof, a top wall having an air outlet

- extending for substantially the full length thereof and a rear wall having an air inlet extending for substantially the full length thereof; adjustable louver means in the front wall air outlet operable in one position to direct air into a desired portion of a room and operable in another position to close the front wall outlet; means in the casing defining an air passage communicating at one end with the air inlet and at 10 the other end with the air outlets and including a movable top wall element operable in one position to form a part of the passage and in another position to close said passage; said element when in open position being inclined forwardly 15 and downwardly from the upper part of the casing and the lower end thereof being spaced from the front wall a distance sufficient to permit the air to pass around the end of the element and upwardly through the top wall outlet when 20 the front wall louvers are in their closed position.
4. An air circulating device for a room comprising an elongated casing having an air inlet in the rear thereof and an air outlet in the front 25 portion thereof; partition means dividing the casing longitudinally into a rear inlet chamber and a front outlet chamber; said means including a downwardly and forwardly extending diagonal portion and a deflecting portion extending upwardly and forwardly from the upper end of the diagonal portion and defining with said diagonal portion a forwardly extending air passage communicating at its forward end with said 30 air outlet in the casing; the diagonal portion having at least one opening therein providing communication between the inlet and outlet chambers; and means providing for the flow of air from the inlet chamber upwardly 35 through the opening in the diagonal portion and directly against the deflecting portion whereby the air entering the outlet chamber is caused to flow forwardly toward the air outlet in the front 40 of the casing.
5. An air circulating device for a room comprising an elongated casing having an inlet opening in the rear portion thereof and an outlet opening in the front thereof; partition means dividing the casing longitudinally into a rear inlet 45 chamber and a front outlet chamber; said means including a downwardly and forwardly extending diagonal portion, and a deflecting portion extending upwardly and forwardly from the upper end of the diagonal portion; said diagonal portion having at least one opening therein providing communication between the inlet and outlet chambers; a deflecting member extending forwardly and downwardly from the forward end of the deflecting portion of the partition and defining with said deflecting portion and the 55 diagonal portion an air passage in the outlet chamber extending forwardly and downwardly; and means providing for the flow of air from the inlet chamber upwardly through the opening in the diagonal portion.
6. An air circulating device for a room comprising an elongated casing having an air inlet in the rear portion thereof and an air outlet in the front thereof; partition means dividing the casing longitudinally into a rear inlet chamber 60 and a front outlet chamber; said means including a downwardly and forwardly extending diagonal portion, and a deflecting portion extending upwardly and forwardly from the upper end of the diagonal portion; said diagonal portion having at least one opening therein providing 65
- communication between the inlet and outlet chambers; a deflecting member extending forwardly and downwardly from the forward end of the deflecting portion of the partition and defining with said deflecting portion and the diagonal portion an air passage in the outlet chamber extending forwardly and downwardly; and means providing for the flow of air from the inlet chamber upwardly through the opening in the diagonal portion.
7. An air circulating device for a room comprising an elongated casing; an upwardly extending partition dividing the casing into a rear inlet chamber and a front outlet chamber; said 15 partition comprising an intermediate diagonal portion extending downwardly and forwardly and having an opening therein providing communication between the inlet and outlet chambers, and an upper deflecting portion extending 20 forwardly and upwardly from the upper end of the diagonal portion and defining with said diagonal portion a forwardly extending air passage; and a blower arranged to provide for the flow of air upwardly and forwardly through 25 the opening in the diagonal portion and directly against the deflecting portion.
8. An air circulating device for a room comprising an elongated casing having an air inlet in the rear and an air outlet in the front thereof; means defining a passage through said casing connecting the inlet and the outlet and including a plate-like element extending lengthwise of the casing and arranged diagonally so as to provide an upper surface sloping forwardly 30 and downwardly toward the air outlet, and an air deflecting member extending lengthwise of the casing and directly above the plate-like element and having its lower surface extending forwardly and upwardly from said plate-like element 35 and defining with the upper surface of the plate-like element a forwardly extending part of the passage; the plate-like element having an air opening therein; and means providing for the flow of air upwardly through the last-named 40 opening and directly against said air deflecting member.
9. An air circulating device comprising a casing having an air inlet and an air outlet and including a bottom wall, a back wall portion, a front wall, a top wall and end walls; the bottom wall and back wall portions being secured together to form a unit and the front, top, and end walls being secured together to form a cover unit removably secured to the first-named 50 unit; a partition in the casing providing with the casing, inlet and outlet air chambers communicating respectively with the air inlet and the air outlet; the partition having an opening therein providing communication between said chambers; a motor driven blower providing for the flow of air through the opening in the partition; the partition and the elements forming the motor driven blower being secured together, and secured to the casing for independent removal therefrom as a unit.
10. An air circulating device for a room comprising an elongated casing having an air inlet in one side thereof and an air outlet in the other side thereof; an upwardly extending partition dividing the casing into a rear inlet chamber and a front outlet chamber communicating respectively with said inlet and said outlet; said partition including a diagonal portion extending 60 downwardly and forwardly towards said 70
- 75

- outlet opening and having an opening there-in providing communication between the inlet and outlet chambers; and deflecting means in said outlet chamber and arranged above said 5 diagonal portion and extending downwardly and forwardly towards said outlet opening and defining with said diagonal portion a forwardly and downwardly extending air passage; and means providing for the flow of air from said 10 inlet chamber upwardly through said opening in the partition and against said deflecting means whereby the air is deflected downwardly and forwardly by said deflecting means and toward said air outlet.
15. 11. A window ventilator unit adapted to be mounted over a window sill, and comprising an elongated casing including a rear wall having an air inlet substantially coextensive therewith, a front wall having an air outlet extending for substantially the entire length thereof; air impelling means arranged within said casing and comprising a pair of blowers arranged within said casing adjacent said air inlet and symmetrically disposed with respect to a transverse 25 median plane passing through the casing; a partition extending lengthwise of the casing and dividing the latter into an inlet chamber extending for the full length thereof and housing said air impelling means, and into an air outlet 30 chamber extending for the full length of said casing and communicating directly with said air outlet; said partition rising from said bottom wall at points adjacent the forward side of said air impelling means and overlying said impelling means; the overlying portion of said 35 partition having a pair of upwardly-directed symmetrically disposed openings therein respectively connected to the discharges of said blowers; and air deflecting and sound deadening 40 means arranged directly above said overlying portion of the partition and defining with said overlying portion a forwardly extending air passage for conducting the air flowing upwardly through said partition openings forwardly toward said outlet opening.
45. 12. A window ventilator unit adapted to be mounted over a window sill, and comprising an elongated casing including bottom, top, front, rear and end walls; said rear wall having an air inlet and said front wall having an air outlet; air impelling means in said casing; a partition extending lengthwise of the casing and forming an inlet chamber receiving air from said inlet and enclosing said air impelling means and forming an outlet chamber communicating with said outlet; said partition rising from said bottom wall and overlying said impelling means; the overlying portion of said partition having an upwardly directed opening for passage of air from 55 said impelling means; and air deflecting means arranged above said overlying portion and defining with said overlying portion a forwardly extending air passage terminating at its forward end at points adjacent said outlet opening for 60 conducting air delivered from said partition opening forwardly towards said outlet.
70. 13. A window ventilator for a room adapted to be arranged adjacent a window opening for said room and comprising a permanently mounted part adapted to be supported upon the sill of said window and having air sealing connections between the sides thereof and the frame of said window and between the top thereof and the sash of said window; a cover part detachably secured to said permanently mounted part; and a

blower-partition unit detachably secured to said permanently mounted part and adapted to be readily removed upon removal of said cover part; said partition-blower unit including a supporting member detachably secured to said permanently mounted part, a partition member fixed to said supporting part and extending longitudinally of the casing and dividing the latter into a rear inlet chamber communicating with the outside atmosphere through an opening in the permanent- 10 ly mounted part and into a front outlet chamber communicating with the room through an opening in the cover part, and a motor-driven blower fixed to said supporting member and to said partition and arranged to discharge air from said 15 inlet chamber through an opening in said partition and into said outlet chamber.

14. In an air circulating device, a casing comprising a base part adapted to be permanently mounted adjacent a room window and a cover 20 part detachably secured to said base part; said base part including a bottom wall adapted to be mounted on a window sill and a rear wall having an air opening therein adapted to communicate with the atmosphere; said cover part having an 25 air opening therein adapted to communicate with the room and including a front wall and a top wall portion fixedly secured together; end walls for said casing secured to one of said parts; and a partition-blower unit arranged within said 30 casing and adapted to be readily removed upon removal of said cover part, and comprising a supporting member detachably secured to the bottom wall of said base part, a partition member fixed to said supporting member and having an 35 opening therein and dividing the casing longitudinally into front and rear air chambers communicating respectively with said openings in the casing, and a motor-blower unit fixed to said supporting member and arranged to provide for 40 the flow of air from one of said air chambers through the opening in the partition and through said other air chamber.

15. Ventilating apparatus comprising wall means defining an enclosing casing structure having an inlet opening in one side thereof and an outlet opening in another side thereof; motor-driven blower means arranged adjacent the inlet opening and having an inlet communicating therewith and having a discharge communicating with the outlet opening; means defining a continuous air passage having an upstream end connected to the discharge of said blower and having a downstream end positioned to discharge air toward said outlet opening in the casing; said 55 means comprising spaced wall parts; one of said wall parts being stationary and forming one side of the air passage and having an opening to which the discharge of the blower is directly connected, the other of said wall parts forming 60 the side of the passage opposite to that formed by the first-named wall part and comprising a stationary element arranged adjacent the opening in the first-named part and a movable element arranged at the downstream side of the stationary part and being pivotally supported at its upstream edge at points directly adjacent the downstream edge of the stationary element; and means for moving said movable element about its pivotal connection so that in one position the 70 movable element extends across said passage and the downstream edge thereof engages the first-named wall part and prevents flow of air through the passage and blower and so that in another position the movable element is arranged 75

in opposed spaced relation with respect to the first-named wall part and defines therewith a portion of said air passage.

16. Ventilating apparatus comprising wall means defining an enclosing casing structure having an inlet opening in one side thereof and an outlet opening in another side thereof; motor-driven blower means arranged adjacent the inlet opening and having an inlet communicating therewith and having a discharge communicating with the outlet opening; means defining a continuous and tortuous sound-deadening air passage having an upstream end connected to the discharge of the blower and having a downstream end arranged to discharge air toward said outlet opening; said means comprising spaced wall parts; one of said wall parts extending in the general direction of said outlet opening in the casing and having an opening therethrough at the upstream portion thereof directly connected to the discharge of said blower; the other of said wall parts being connected at its upstream edge to the upstream edge of said first-named part and extending first away from the latter and then in a downstream direction so as to deflect the air discharged from said opening and direct such air toward said outlet opening in the casing structure; said other wall part comprising a stationary element connected at its upstream edge to the upstream edge of the first-named wall part, and a movable damper element arranged at the downstream side of said stationary element and being pivotally supported at its upstream edge at points directly adjacent the downstream edge of said stationary element; and means for moving said movable element about its pivotal connection so that in one position said movable element extends across said passage and the downstream edge thereof engages the first-named wall part and thereby prevents flow of air through said passage and blower and so that in another position the movable element

is arranged in opposed spaced relation with respect to the first-named wall part and defines therewith a portion of said air passage.

17. A window ventilator unit adapted to be mounted over a window sill, and comprising a bottom wall supported over said window sill; a rear wall having an air inlet opening therein extending for substantially the full length thereof and communicating directly with the atmosphere; a front wall having an outlet opening therein extending for substantially the full length thereof and adapted to communicate directly with the room space; a top wall; end walls joining the rear, front and top walls and providing therewith a casing structure; a partition arranged in said casing and extending from end wall to end wall thereof and from bottom wall to top wall thereof and dividing the interior of said casing into a rear inlet chamber communicating directly with the air inlet opening and a front outlet chamber connected directly with the air outlet opening; said partition having an opening therethrough connecting said chambers; a motor-driven blower unit arranged in said inlet chamber and operable to discharge air from the inlet chamber through said opening in the partition into the outlet chamber; and means in the outlet chamber defining a continuous air passage having an upstream end communicating directly with the opening in the partition, and a downstream end positioned to discharge air through the outlet opening in the front wall; said means including a movable wall element pivotally supported along its upstream edge and operable in one position to extend across said passage and engage the other side thereof so as to close entirely said passage and prevent flow of air through the opening in said partition, and operable in another position to function as a part of the defining wall structure of said passage.
